UNITED STATES PATENT OFFICE.

WILLIAM E. DONEHOWER, JOHN J. DOWNS, AND JOHN A. DWYER, OF
NORTH PLATTE, NEBRASKA.

REFRIGERATING-CAR.

SPECIFICATION forming part of Letters Patent No. 634,447, dated October 10, 1899.

Application filed September 3, 1898. Serial No. 690,247. (No model.)

To all whom it may concern:

Be it known that we, WILLIAM E. DONEHOWER, JOHN J. DOWNS, and JOHN A. DWYER, citizens of the United States, residing at North 5 Platte, in the county of Lincoln and State of Nebraska, have invented certain new and useful Improvements in Refrigerating-Cars; and we do hereby declare the following to be a full, clear, and exact description of the invention, 10 such as will enable others skilled in the art to which it appertains to make and use the same.

Our invention relates to certain new and useful improvements in the construction and combination of parts necessary to produce a 15 refrigerating-car, which will be hereinafter fully described and claimed, and illustrated in the accompanying drawings, made a part of this application.

The object of our invention, among others, 20 is to provide a refrigerating apparatus located at any desired point within the car or upon the train and certain additional means whereby motive power is obtained directly from the car-axle, as set forth, thus obviating the 25 necessity of a special motor for running the apparatus.

In the accompanying drawings, Figure 1 is 30 a side elevation of a car provided with our refrigerating mechanism, the front side of said car being removed to disclose said mechanism. Fig. 2 is a plan view showing the arrangement of pipes in the bottom of tank, relative position of pumps, &c. Fig. 3 is an elevation of the end of the car with the end 35 wall removed. Fig. 4 illustrates in section the valve used for releasing surplus air from the air-tank. Figs. 5, 6, and 7 illustrate the valve mechanism employed to regulate the quantity of air used in running the ammonia- 40 pump.

For convenience in describing the various details of our invention reference will be made thereto by means of numerals, the same numeral being employed to designate the 45 same part in the several views.

Briefly stated, our invention consists in mechanism adapted to take power from the axle of the car, whereby the refrigerating processes are effected. In the present case

we employ this power primarily to operate an 50 air-pump, which stores away a quantity of compressed air in an air-tank. This air is then used as needed for the operation of the refrigerating mechanism.

In carrying out our invention we rigidly 55 secure to the car-axle 1 the driving-gear 2, designed to mesh with the gear 3, keyed to the journal 4, the ends of which are mounted in the bearing-blocks 5. The driving-gear 2 is concave upon its outer face, as clearly shown 60 in Fig. 3, the object of the concavity thus provided being to compensate for the rocking position or lateral swaying of the body of the car with respect to the carrying-axle thereof, thus enabling the gear 3 to always 65 remain in mesh with the gear 2, even though the car-body be laterally inclined to one side or the other, as will be incident to a rapid movement of the train.

Rigidly attached to gear 3 is gear 6, which 70 meshes with pump-gear 7, mounted in bearing-blocks 8. The bearing-blocks 5 and 8 are respectively held rigidly in position by the guide-frames 9 and 10, the object of thus mounting said blocks being to enable them 75 to move up or down to compensate for any lateral motion that may be imposed upon the car and also to compensate for the spring of the car. The shaft of the gear 7 carries the crank 11, to which is connected the piston-rod 12, designed to operate the air-pump 13. Said pump is of the ordinary construction and preferably pumps air at one end only, where it is provided with a receiving-valve 80 14 and an exit-valve, which latter permits the air drawn into the cylinder by one stroke of the piston to pass out by the next stroke through the pipe 14 into the compressed-air tank 15, located, preferably, beneath the car.

Conveniently located within the car, preferably near the air-pump 13 and disposed parallel thereto, is the double-cylinder pump 16, one cylinder 17 of which is provided with the chest 18, which communicates therewith. By means of the pipe 19 this chest is connected 90 with the air-tank. Said pipe is provided, preferably at a point near the tank, with a suitable valve 20, by which any desired amount

of air may be admitted from the air-tank to the chest 18. Said chest 18 and cylinder 19 are similar to the chest and cylinder of an ordinary steam-engine, but in this case we use 5 compressed air instead of steam as a motive power for driving the piston. The other cylinder 21 constitutes an ammonia-pump. The piston in this pump is connected to the piston in cylinder 17 by the piston-rod 22, so that 10 the pump 21 is operated by the action of the compressed air in the opposite cylinder. This ammonia-pump is provided with valves similar to those employed in pump 13, and when in motion the ammonia is drawn from pipe 15 23 through one of these valves into the cylinder 21 and is expelled through the other valve into pipe 24. Said pipe 23 connects the ammonia-pump with the ammonia-tank 23^a, which is preferably located in the corner of 20 the car adjacent to that occupied by the pumps.

Across the end of the car, immediately above the pumps, &c., we prefer to locate the water tank or condenser 25, which we keep 25 partially filled with water. The pipe 24, into which ammonia is driven by the pump 21, extends upwardly through this tank to the top of the car, where it extends back and forth laterally and longitudinally any desired number 30 of times. It is here illustrated, Figs. 1 and 3, as forming the parallel sections 24^a and 24^b. It then forms the section 24^c, which from a point in the top of the car immediately over one corner of tank 25 descends to the bottom 35 of said tank, where it forms the series of zig-zag sections 24^d, which lie on said bottom, passing back and forth across the entire width thereof and finally terminating in the upwardly-extending section 24^e, which enters 40 the ammonia-tank, into which it again discharges the ammonia, said ammonia having been of course condensed as it passed through the zigzag sections in the bottom of the condenser, said sections being always covered 45 with water. Pipe 26 leads from the air-tank 15 to a point beneath the surface of the water in the condenser 25. Through this pipe a jet of air is constantly passed and is released in the water, the object thereof being 50 to keep the water at a proper temperature to perform its part of the work in the process of refrigeration. At the point where said pipe connects with the air-tank is the safety-valve illustrated in Fig. 4. Said valve consists of 55 the valve-chamber 27, which is provided with the valve 28, suitably seated therein. Rigidly attached to said valve is the stem 29, secured to the lower end of which is the plate 30. Between said plate and the lower end of 60 valve-chamber 27 we locate the expansion-spring 31, which tends to hold valve 28 normally closed. When, however, the pressure in the air-tank becomes too great, said pressure will overcome the force of spring 31 and 65 will lift valve 28 from its seat, which will per-

mit the excessive amount of air to escape. By this means any excessive amount of air which may be stored in the air-tank is not wasted, but is passed through the water in the condenser for the purpose above specified. 70 The upper part of valve-chamber above valve 28 is connected with the air-tank by a small pipe 32, which permits a small quantity of air to be always passing from said tank into the water in the condenser so long as there is 75 compressed air in the air-tank. The top of valve-chamber 27 is adapted to receive the threaded cap 27^a, to which the pipe 26 is attached.

The valve 20 (illustrated in Figs. 5, 6, and 80 7) consists of the valve-chamber 33, to the top of which is rigidly attached the annular plate 34, having a series of graduations 35, which may be numbered, if desired, as referred to hereinafter, and the valve 36, having the horizontal aperture 37 and carrying on its top projection the pointer 38. The conical valve 36 is held in operative position by the cap-nut 39, threaded onto the stem 40, projecting from 85 the bottom of said valve.

In order to determine the desired speed which will be imparted to the pumping apparatus, the refrigerator will be tested in the shops before being placed upon the road as follows: The tank 15 will be filled with air 90 and valve 20 will be opened sufficiently to start the pump 21. A thermometer will be placed in the car, and when the air therein is lowered to the fullest extent possible with the pump working at this speed the temperature indicated by the thermometer will be recorded opposite the proper graduation on the dial-plate 34 of valve. The valve may then be opened a little more, and after the thermometer has indicated the lowest temperature resulting therefrom this position of the valve is also indicated in degrees of temperature on the dial-plate. The valve may be opened still farther and the proper registration made, and so on until the maximum 100 and minimum degrees of temperature desired are indicated, thus making it possible for the attendant to merely turn the valve till the indicating-finger registers with the degree of temperature desired. 105

We claim—

1. In a refrigerator-car, a pressure-regulated air-valve consisting of a housing or chamber 27, a valve 28 seated therein, means to hold said valve normally closed, and an 110 escape-pipe 32 connecting the reservoir and said housing whereby a limited quantity of air is constantly permitted to pass from the reservoir into said housing while the pressure in the reservoir is insufficient to raise said 115 valve, as and for the purpose set forth.

2. A pressure-regulated valve consisting of a housing, a valve-seat provided therein, a valve located in said seat and having a spring 120 to hold it normally down, in combination 125

with an independent pipe or opening 32 connecting the upper part of said housing to the reservoir, whereby a constant escape of air from the reservoir will be permitted into the
5 upper part of the housing before the pressure in the reservoir is sufficient to raise said valve, as specified and for the purpose set forth.

In testimony whereof we affix our signatures in presence of two witnesses.
